CLOTHESLINE PROP

George D. Holmes, Alvin, Tex.

Application September 7, 1951, Serial No. 245,541

2 Claims. (Cl. 248—353)

1

This invention relates to a clothes line prop, and more particularly, has reference to a prop so formed as to engage a clothes line in a manner to be held against slippage longitudinally of said line.

One important object is to provide a clothes prop as described that can be attached with considerable facility to any available piece of suitable lumber, without requirement of tools or special skill.

Another important object is to provide a prop of the type stated which, when attached to a suitable piece of lumber or the like, will support sagging clothes lines, whether said lines be formed of metal or cordage material, without possibility of slipping longitudinally of the line or falling out of engagement with the line.

Yet another important object is to provide a clothes line prop as described which can be applied to a clothes line speedily, at any desired location, and which when applied will be positive in action and will not injure the line.

A further important object is to provide a clothes line prop in which the line engaging means includes a series of pins arranged in different planes so as to deform the line longitudinally in a manner to grip the line securely, said pins being alternately inclined in different directions, so as to preclude the tendency toward disengaging of the line and prop.

A further important object is to provide a clothes line prop that will be of simple construction, will be ruggedly constructed, and will be capable of manufacture at relatively low cost.

Other objects will appear from the following description, the claims appended thereto, and from the annexed drawing, in which like reference characters designate like parts throughout the several views, and wherein:

Figure 1 is a perspective view of a clothes line prop formed in accordance with the present invention, as it appears when applied to a clothes line;

Figure 2 is an enlarged top plan view;

Figure 3 is a front elevational view, the post being illustrated fragmentarily;

Figure 4 is a side elevational view;

Figure 5 is a longitudinal sectional view taken on line 5—5 of Figure 3;

Figure 6 is a transverse sectional view taken substantially on line 6—6 of Figure 3, and

Figure 7 is an enlarged perspective view of the line-engaging plates, as they appear when disassociated from the post.

Referring to the drawings in detail, a post 10

2

is formed from any suitable piece of material, such as an elongated length of lumber. In this connection, the clothes prop constituting the present invention is so formed as to permit the use of any piece of lumber, it being possible, in utilizing my invention, to reduce the cost of manufacture by selling the line-engaging means without the post 10, so that a purchaser is enabled to subsequently apply said means to any available piece of wood stock.

At its lower end, the post 10 is tapered to provide a ground point 11, to facilitate the placement of the lower end of the post in engagement with the ground surface.

In carrying out the invention, I provide a front plate 12 formed from a suitable piece of flat metal material. Intermediate the upper and lower ends of the front plate, the side edges thereof are slit transversely as at 14, said slits extending inwardly from the side edges of the plate a short distance.

Between the slits 14 and the bottom edge of the front plate, the side portions of said plate are formed with rearwardly extended flange members of right angled cross sectional shape, each flange member including a leg 16 arranged perpendicularly to the general plane of the plate, and formed integrally with an outwardly extending leg 18 that is disposed in parallelism with and is spaced rearwardly from the plane of the main body of the plate. Medially between the opposite ends of the leg 18 of the flange member, I form in said leg an aperture 20.

As may be noted from Figure 6, the provision of the flange members permits the front plate to be applied to the front and side surfaces of the post 10, the legs 16 engaging against the side surfaces of the post, while the main body of the plate is in contact with the front surface of said post. The legs 18 of the flange members, as will be seen from Figure 6, are spaced forwardly of the back surface of the post 10, and extend outwardly in opposite directions from the side surfaces of said post.

Between the slits 14 and the upper end of the plate 12, said plate is provided with a widened upper portion, defining wings 22 projecting laterally of and beyond the post. A top flange 24 is integral with the upper edge of the widened upper portion of the front plate, extending rearwardly in a plane perpendicular to the plane of the main body of the front plate, so as to overlie the top of the post 10. As a result, if it is desired to hammer the post into the ground surface, the top flange will receive the force of

the blows of the hammering tool, thus to prevent damage to the upper end of the post, and thereby assure long life to the clothes line prop.

From the foregoing, it will be noted that the front plate 12 is of T-shape and will be disposed on the post or prop 10 in an upstanding position. The flange 24 projects laterally from the top edge of the head of the T-shaped front plate while the stem of the plate 12 carries the side members or legs 16 which extend perpendicularly therefrom along each of the side edges of the stem and in the same direction as the flange 24, the outwardly extending leg 18 carried by the free end of each of the side members or legs 16 constituting securing plates.

Rigidly secured to the widened upper portion of the front plate 12 is a series of line-engaging pins, that project outwardly and forwardly from the front plate, and are spaced transversely of said plate. The series of pins includes a pair of outer pins 26, that are inclined upwardly from the front plate, and medially disposed between the outer pins 26 is an inner pin 28, that is inclined downwardly from the front plate, and is disposed, at its inner end, at a plane lower than the plane of the inner ends of the outer pins (see Figures 4 and 5).

For the purpose of fixedly connecting the front plate 12 to the post 10, I form the lower portion of the front plate with a plurality of struck lugs 30, these preferably being triangularly spaced to make the connection of the front plate to the post as rigid as possible.

A back plate 32 is formed to a width somewhat greater than that of the post 10, and comprises a single flat piece of metal material coextensive in length with the front plate 12. In this connection, it may be noted that the top edge of the back plate 32 is flush with the top surface of the post 10. Therefore, since the top flange 24 of the front plate overlies said top surface of the post, the top flange affords protection to the back plate 32, so that said back plate is not struck upon its top edge when the post 10 is hammered into the ground surface.

Formed in the back plate 32, intermediate the upper and lower ends thereof, and spaced inwardly from the side edges of said back plate are openings 34, that register with the openings 20. Bolts 35 are extended through the registering openings, and receive wing nuts 36, whereby the front and back plates are securely clamped in position against the post. The back plate 32, in this connection, serves the purpose of rigidifying the connection of the front plate 12 to the post, and it is important to note in this regard that the back plate and front plate are readily connected to one another and to the post without the need of special tools or skills.

It should be noted that the back plate 32 is arranged in spaced face-to-face relation with the securing plates 18 and the outer edge of the flange 24 when the prop head is assembled on the post 10, and the bolts 35 extending through apertures 20 in the securing plates 18 and through the openings 34 in the back plate 32 will draw the front plate 12 and the back plate 32 towards each other as the wing nuts 36 are threaded upon the end of the bolts 35 so as to clampingly engage the prop or post 10 with the flange 24 overlying one end of the prop, as clearly shown in Figure 4.

In use, the clothes line prop is engaged with a clothes line 38 in the manner illustrated in Figure 1. In interengaging the line with the prop, the

line is cast over the outer pins 26 and under the inner pin 28. Since the inner pin is offset from the plane of the outer pins, the line is deformed longitudinally, so as to be tensionably gripped by the pins, in a manner to prevent relative slippage between the line and the prop. Further, since the outer pins are inclined upwardly, while the inner pin is inclined downwardly, any tendency toward disengagement of the clothes line prop from the line is effectively precluded.

It is believed clear that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor changes in construction that may be permitted within the scope of the appended claims.

What is claimed is:

1. A head for a clothes line prop comprising an upstanding front plate of T-shape having a flange projecting laterally from the top edge of the head of said plate, the stem of said plate having a side member extending perpendicularly along each of its side edges and in the same direction as said flange, a securing plate carried by the free end of each of said side members and extending outwardly therefrom, a back plate arranged in spaced face-to-face relation with said securing plates and with the outer edge of said flange, means extending through each of said securing plates and said back plate to draw said front plate and said back plate towards each other to clampingly engage the prop with said flange overlying one end of said prop, and a series of line engaging pins carried by the head of said front plate.

2. A head for a clothes line prop comprising an upstanding front plate of T-shape having a flange projecting laterally from the top edge of the head of said plate, the stem of said plate having a side member extending perpendicularly along each of its side edges and in the same direction as said flange, a securing plate carried by the free end of each of said side members and extending outwardly therefrom, a back plate arranged in spaced face-to-face relation with said securing plates and with the outer edge of said flange, means extending through each of said securing plates and said back plate to draw said front plate and said back plate towards each other to clampingly engage the prop with said flange overlying one end of said prop, and a series of line engaging pins carried by the head of said front plate, said series including a pair of outer pins inclined in one direction and a center pin disposed between said outer pins and inclined in an opposite direction.
